Specification for Design.

Patented Dec. 6, 1921.

Application filed December 28, 1920. Serial No. 433,856. Term of patent 14 years.

To all whom it may concern:

Be it known that I, TRUE M. AVERY, a citizen of the United States, residing at Glens Falls, in the county of Warren and State of New York, have invented a new, original, and ornamental Design for Lifting-Jacks, of which the following is a specification, reference being had to the accompanying drawing, forming part thereof.

The figure is a perspective view of a lifting jack, showing my new design.

I claim:

The ornamental design for a lifting jack, as shown.

In testimony whereof, I affix my signature.

TRUE M. AVERY.
